UNITED STATES PATENT OFFICE.

VALENTIN ODHNER, OF ST. PETERSBURG, RUSSIA.

CALCULATING-MACHINE.

No. 885,614.

Specification of Letters Patent. Patented April 21, 1908.

Application filed June 5, 1907. Serial No. 377,383.

To all whom it may concern:

Be it known that I, VALENTIN ODHNER, manufacturer, a subject of the King of Sweden, residing at No. 4 Tarakanoffski Per., at 5 St. Petersburg, Russia, have invented certain new and useful Improvements in Calculating-Machines; and I do hereby declare the following to be a full, clear, and exact description of the invention, such as will enable 10 others skilled in the art to which it appertains to make and use the same.

The present invention relates to means in calculating machines for returning numbered disks into the zero position, being especially adapted for use with that type of 15 machines covered by United States patents to Odhner numbered 209,416 and 514,725.

As is known in calculating machines the 20 number of times the handle is rotated is indicated by numbered disks.

Now the present invention relates to a device for returning these numbered disks into the zero position by rotating and displacing the axle which carries them. This axle has 25 hitherto been rotated directly, by a winged disk, for example, placed on the same, and the winged disk had to be rotated twice through an angle of 180° every time. To attend to the machine in this manner is 30 troublesome. It is also uncertain, because the handle may be turned too far and a numbered disk may thus be brought away from the zero position, particularly when operating quickly.

35 An important object of the present invention is to remove these defects.

In order that the invention may be clearly understood, reference is made to the accompanying drawing in which one embodiment is 40 represented by way of example, and in which:

Figure 1 is a front elevation of a calculating machine with the new device; Fig. 2 is a vertical transverse section through the same; Fig. 3 shows the new device in elevation seen 45 from the end, the cover having been removed; Fig. 4 is a section on the line A—B of Fig. 3 on an enlarged scale, and Fig. 5 shows one form of a detail.

Similar letters of reference denote similar 50 parts in all views.

The numbered disks *a* (Fig. 2) are provided in known manner with displaceable teeth *b* which engage in the teeth of the counting wheels *e*. The latter engage in the teeth of

driving wheels *f* which are loose on a common axle *d*, and each of the wheels *f* carries laterally a numbered disk *g*. The rounded end of a lever *k* is pressed by a spring *y* between the teeth of the wheels *f* and holds these firmly in their stationary position at 60 any time.

At the side of the machine there is a case *C* arranged in which the new device for setting the numbered disks *g* to zero is placed. A ring *c* which is fastened on the frame of the 65 machine is loose on the end of the axle *d* which projects out of the machine, and this ring *c* has a notch or incision *v* which slopes upwardly. Opposite this ring a toothed wheel *i* provided with a lug or shoulder *i*¹ is arranged fixed on the axle *d* in such a manner that this shoulder lies against the ring *c* and engages in the incision *v* in the zero position. Further, a spring *x* is provided on the axle *d* 70 between a collar *x*¹ and the side of the frame of the machine, and this spring *x* tends to press the axle *d* and with it the shoulder *i*¹ to the left against the ring *c*. Each of the disks *g* possesses a pin *l* against which a pin *m* can lie when the axle *d* is displaced to the 75 right one pin *m* being provided on the axle *d* for each disk. If the axle *d* is rotated by means of the toothed wheel *i* the shoulder *i*¹ slides out of the incision *v*, the axle *d* is thereby displaced to the right, and consequently 80 the numbered disks become coupled in known manner with the axle *d* by means of the pins *m* and *l* and are rotated by the same, until the shoulder *i*¹ falls into the incision *v* and the 85 disks are disengaged from the axle *d*.

An axle *n* with a toothed wheel *q* is journaled in the case *C*; this wheel *q* engages with the toothed wheel *i* and possesses, for example, three times as many teeth as the latter. With the toothed wheel *q* there is rigidly connected a ratchet wheel *r*, the number of teeth of which is a multiple of the ratio of transmission between the toothed wheels *i* and *q*, and has for example 15 teeth. Further a hub *s* carrying a key-lever *Z* is loose on the 95 axle *n*; this lever projects out of the case through a slot (Fig. 1) and carries a pin *h*. A pawl *h*¹ is on the latter and is pressed by a spring *t* into the teeth of the ratchet wheel *r*. A spring *t*¹ holds the lever *Z* in its normal position. The movement of the hub of the lever *Z* is in the present case limited to 120°, so that when the lever is rotated through 100 105

this angle the axle d is rotated one complete revolution in consequence of the ratio of transmission of the toothed wheels.

The manner in which the device operates is as follows:—When the lever Z is depressed the pawl h^1 engages in the teeth of the ratchet wheel r , whereby the latter and with it the toothed wheel q is rotated 120° . The latter transmits its rotation to the toothed wheel i 10 and causes a complete revolution of the axle d in consequence of the ratio of transmission. At the commencement of the rotation the shoulder i^1 of the toothed wheel i slides on the face of the incision v of the ring c which 15 slopes up in a slanting direction, whereby the axle d is displaced to the right. The numbered disks q are coupled with the axle d and are rotated by the latter into their zero position, whereupon the projection i^1 of the 20 toothed wheel i falls into the notch v again and the axle d is thereby displaced to the left again. The numbered disks can then be rotated independently of the axle d . When 25 the lever Z returns to its normal position the toothed wheels q and i remain stationary and with them also the axle d .

As the same teeth of the 15 teeth with which the ratchet wheel r is provided always operate, and as the pawl h^1 might possibly 30 jump over one tooth and thus cause a mistake, it is preferable to provide the ratchet wheel r with only three ratchet teeth h^1 which are placed 120° one from another (Fig. 35 5). i. e. to make $M:N$, the ratio of the number of the teeth of the ratchet wheel to unity equal to the ratio of transmission between the toothed wheels q and i . Thus each revolution of the axle d always corresponds to only one tooth of the ratchet wheel, so that it 40 is not possible to make a mistake when setting the disks to zero.

What I claim as my invention and desire to secure by Letters Patent is:

1. In a calculating machine, the combination of numbered disks and an axle for returning said numbered disks into the zero position, with a rotary pivot-shaft, a lever loosely mounted on said pivot-shaft, a spring for returning said lever, a driving member on 45 said axle adapted to displace said axle longitudinally when the same is rotated, a gear wheel on said pivot adapted to drive said driving member, and ratchet mechanism connected with said lever adapted to drive 50 said gear wheel when said lever is rotated forward, the ratio of transmission of said gear wheel and driving member being equal to the ratio of the angle through which said lever is rotated to one complete revolution, 55 whereby when said lever is rotated forward said axle is displaced and rotated one revolution.

2. In a calculating machine, the combination of numbered disks and an axle for re-

turning said numbered disks into the zero position, with a pivot, a lever on said pivot, gearing connected with said pivot adapted to drive said axle, ratchet mechanism connected with said lever adapted to drive said gear when said lever is rotated forward, and means adapted to engage said lever for limiting the stroke of said lever corresponding to the ratio of transmission of said gearing, the ratio of transmission of said gearing being equal to the ratio of the angle through which 75 said lever is rotated to one complete revolution, whereby when said lever is rotated forward said axle is rotated one revolution.

3. In a calculating machine, the combination of numbered disks and an axle for returning said numbered disks into the zero position, with a case having an opening and a slot, the end of said axle passing through said opening into said case, a ring having a notch in said case round said axle, a toothed wheel 85 provided with a lug normally in said notch fixed on said axle, a pivot in said case, a lever on said pivot extending through said slot, a toothed wheel carrying a ratchet wheel on said pivot gearing with said former toothed 90 wheel, and a spring-pressed ratchet on said lever for driving said ratchet wheel when said lever is moved forward, the ratio of transmission of said toothed wheels being equal to the ratio of the angle through which said 95 lever is rotated to 360° , whereby when said lever is rotated forward said axle is displaced and rotated one revolution as set forth.

4. In a calculating machine, the combination of numbered disks and an axle for returning said numbered disks into the zero position, with a case having an opening and a slot, the end of said axle passing through said opening into said case, a ring having a notch in said case round said axle, a toothed wheel 100 provided with a lug normally in said notch fixed on said axle, a pivot in said case, a lever on said pivot extending through said slot, a toothed wheel carrying a ratchet wheel on said pivot gearing with said former toothed 105 wheel, and a spring-pressed ratchet on said lever for driving said ratchet wheel when said lever is moved forward, the ratio of transmission of said toothed wheels being equal to the ratio of the angle through which said 110 lever is rotated to 360° , and said slot limiting the stroke of said lever corresponding to the ratio of transmission of said toothed wheels, whereby when said lever is rotated forward said axle is displaced and rotated one revolution as set forth.

5. In a calculating machine, the combination of numbered disks and an axle for returning said numbered disks into the zero position, with a pivot, a lever carried by said pivot, gearing connected with said pivot adapted to drive said axle, ratchet mechanism connected with said lever adapted to

drive said gearing when said lever is rotated forward, the ratio of transmission of said gearing being equal to the ratio of the angle through which said lever is rotated to one complete revolution; whereby when said lever is rotated forward said axle is rotated one revolution.

In testimony whereof I affix my signature in presence of two witnesses.
